US0D1052474S

(12) **United States Design Patent** (10) **Patent No.:** **US D1,052,474 S**
(45) **Date of Patent:** **** Nov. 26, 2024**

(54) **ELECTRIC LIFT TRANSFER CHAIR**

(71) Applicant: **Xiangfali Medical Technology (Fujian) Co., Ltd.**, Zhangzhou (CN)

(72) Inventor: **Shuifa Yu**, Xiamen (CN)

(73) Assignee: **XIANGFALI MEDICAL TECHNOLOGY (FUJIAN) CO., LTD.**, Zhangzhou (CN)

(**) Term: **15 Years**

(21) Appl. No.: **29/863,485**

(22) Filed: **Dec. 20, 2022**

(51) **LOC (14) Cl.** **12-12**

(52) **U.S. Cl.**

USPC **D12/131**

(58) **Field of Classification Search**
